D11-7. OR D11,413 EX

DESIGN FOR A BRACELET.

Specification forming part of Design No. **11,413**, dated September 16, 1879; application filed May 14, 1879.
[Term of patent 7 years.]

UNITED STATES PATENT OFFICE.

THOMAS G. BROWN, OF NEW YORK, N. Y.

DESIGN FOR A BRACELET.

Specification forming part of Design No. **11,413**, dated September 16, 1879; application filed May 14, 1879.
[Term of patent 7 years.]

To all whom it may concern:

Be it known that I, THOMAS G. BROWN, of the city, county, and State of New York, have invented a new and Improved Design for Bracelets, of which the following is a specification.

A represents the bracelet, the two ends whereof are clasped together at B. To the two ends are attached rings, from which depend a right-angular pendant, C, on the lower bar whereof are placed rings forming the combination-lock. This pendant swings freely and adds greatly to the appearance of

the style of bracelets in which combination-locks are used.

What I claim as my invention is—
The design for a bracelet, consisting of the pendant C, in representation of a lock suspended from rings on the clasped ends of the bracelet, substantially as shown and described in the accompanying illustration.

THOMAS G. BROWN.
